UNITED STATES PATENT OFFICE.

FRANK E. PETRI, OF PEORIA, ILLINOIS.

CONNECTION PLUG.

Application filed February 4, 1924. Serial No. 690,438.

To all whom it may concern:

Be it known that I, FRANK E. PETRI, a citizen of the United States, and a resident of Peoria, in the county of Peoria and State 5 of Illinois, have invented certain new and useful Improvements in Connection Plugs, of which the following is a full, clear, and exact description, reference being had to the accompanying drawing, forming part of 10 this specification.

My invention relates primarily to electrical devices wherein it is desired to connect and disconnect a source of current supply with a device operated by electricity, my 15 invention residing in the plug which forms a part of the means for connecting or disconnecting the current supply.

One object of my invention is the provision of a heavy duty plug which, while not 20 intended to carry an excessive current, is constructed to withstand hard and continuous service.

Another object of my invention is the provision of means whereby when the plug 25 is operated to connect or disconnect a current supply, the wires which are attached to the plug are not twisted or untwisted during the connecting or disconnecting operation.

30 Another object of my invention is the construction and arrangement of parts whereby when the plug is screwed down into the socket, proper electrical connections between the parts are assured.

35 Other objects of my invention, and the novelty thereof will be hereinafter more fully set forth and specifically pointed out in the claims.

In the accompanying drawing:

40 Fig. 1 is an elevation of my plug completely assembled.

Fig. 2 is a sectional elevation of Fig. 1.

Fig. 3 is a view of the major parts of the device disassembled.

45 The same numerals of reference are used to indicate identical parts in all the figures.

My plug consists primarily of three major 50 portions, an insulating handle portion 4, a threaded portion 5, and an insulated terminal portion 6. As shown more clearly in Fig. 2 the portion 4 carries a metal ring 7 which carries a pair of screws 8, the latter passing through suitable openings in 55 the side of the portion 4, this portion being centrally apertured as at 9 to permit the

wires or conductors to pass through it. The threaded portion 5 is turned inwardly at its lower end as shown at 10, and its upper end is provided with bayonet joint slots 11 to be engaged by the screws 8. The terminal portion 6 which is preferably made of porcelain or other suitable insulating material is provided with a contact screw and washer 12, between which and the base 13 therefor one of the wires is clamped, the 60 base 13 being held in place by a tubular rivet 14 through which the wire passes, this construction being similar to corresponding parts of the ordinary connection plug.

The upper portion of the terminal portion 70 6 is surrounded by a metal band 15 which carries a binder 16 to which the other wire for the circuit is attached, the band 15 being shaped to engage the inner surface and a portion of the lower end of the metal 75 ring 7.

When assembled as in Fig. 2, the terminal portion 6 is held in place by the inturned portion 10 of the threaded portion 5 coming in contact with the shoulder 16 formed 80 near the lower end of the member 6, though the member 6 is free to turn in the assembled structure to the end that the portions 4 and 5 may be turned about it when making the connection. As soon as the plug 85 has been screwed into the socket to a point where the screw and washer 12 come in contact with the center connection of the socket, the portion 6 is forced upward with relation to the balance of the plug to cause 90 the metal ring 15 to engage with the ring 7 and make a proper electrical connection between the two, thus establishing a circuit from the threaded sleeve 5, through the ring 7 to the band 15 and binder 16, the tightness 95 of this connection being determined by the pressure produced by the threaded portion 5.

The plug may be readily disassembled 100 by loosening the screws 8 and disengaging the bayonet connection between these screws and the threaded portion 5, whereupon the terminal portion 6 may be removed from the threaded portion 5, to enable the wires to be properly connected to their respective points, it being remembered 105 that the wires are first threaded through the hole 9 of the insulator 4, and then connected to the binders of the terminal portion 6 after which the portion 4 is brought 110

into contact with the portion 6 and the threaded portion 5 replaced and the screws 8 tightened, thus completing the assembly.

By inserting the ring 7 in the insulator 4, this insulator is materially reinforced so that should it or the assembled plug be accidentally dropped, it will not be broken.

By making the insulator 4 large and substantial as shown, a sufficient handhold is provided to enable the plug to be readily attached to or removed from the socket.

It is to be noted that the screws 8, when properly tightened are a sufficient distance below the surface of the insulating portion 4 to preclude the possibility of touching them with the finger so that there is no likelihood of the user coming in contact with any of the live connections during attachment or detachment of the plug.

20 By placing the bayonet joint slots 11, and forming them to lead in the direction of the threads of the portion 5, the plug will not come apart even though the screws 8 are not properly tightened and when the plug is attached to a socket the action of the thread engagement will pull the portion 5 downward with relation to the rest of the plug and so establish a good connection between the screws 8 and the slots 11.

30 It is to be noted that when the plug is screwed into the socket, the pressure exerted by the engagement of the threads serves to tighten and hold in place all of the electrical connections, and further that the pres-

sure exerted on the various parts by this engagement is uniform meaning that if the washer and screw 12 is forced against the center contact with a ten pound pressure, or any other amount, that same pressure will be exerted between the band 15 and ring 7, and between the points of connection between the ring 7 and the threaded portion 5.

Having thus fully described by invention, I claim:

1. In an attachment plug the combination of an insulating handle portion, a reinforcing contact ring imbedded therein, a threaded sleeve portion provided with bayonet joint connecting means cooperating with the contact ring, a terminal carrying portion retained in place by the threaded sleeve portion, a contact band carried by the terminal contact portion cooperating with the contact ring of the insulated handle portion when the plug is attached to a socket. 55

2. In an attachment plug the combination of an insulating handle portion, a reinforcing and contact ring imbedded therein, screws carried by said ring, a threaded sleeve portion for engagement with the socket, bayonet joint slots for engagement with the screws of the contact ring, a terminal carrying portion loosely mounted in the threaded sleeve portion and carrying a central contact at one end and a contact band at the other end to cooperate with the contact ring of the handle portion. 65

FRANK E. PETRI.
